UNITED STATES PATENT OFFICE.

ALBERT J. FORD, OF NEW YORK, N. Y., ASSIGNOR TO THE FUCHS & LANG MANUFACTURING COMPANY, A CORPORATION OF NEW YORK.

AUTOMATIC TRIP MECHANISM FOR PRINTING-PRESSES.

1,034,776.

Specification of Letters Patent.

Patented Aug. 6, 1912.

Application filed February 4, 1909. Serial No. 475,952.

To all whom it may concern:

Be it known that I, ALBERT J. FORD, a citizen of the United States, residing at the borough of Manhattan, city of New York, 5 in the county of New York and State of New York, have invented a certain new and useful Improvement in Automatic Trip Mechanism for Printing-Presses, of which the following is a specification, reference being had therein to the accompanying drawings, forming part thereof.

My invention relates to a device for automatically tripping a printing press or throwing its printing couple out of operation in case of the absence of a sheet at the time when, in the normal operation of the press, a sheet is fed to the printing couple to receive the impression.

The invention is applicable, in some respects, to printing presses of various forms, but is particularly designed for use in connection with presses having rotary impression cylinders and operating upon sheets of tin plate or other stiff material.

Generally stated, the object of my invention is to produce a device of the kind above described which shall be simple in construction and reliable in operation, and to this end the invention consists in the automatic trip mechanism hereinafter described, as defined in the succeeding claims.

More specific objects of the invention and the features of construction by which they are attained will be pointed out in connection with the following description of the illustrated embodiment of the invention.

I will now describe the embodiment of my invention illustrated in the accompanying drawings, and will thereafter point out my 40 invention in claims.

In the drawings, Figure 1 is a side elevation of a portion of a printing press illustrating a trip mechanism embodying the present invention. Fig. 2 is an end view of 45 the trip mechanism. Fig. 3 is a detail view, partly in section, of the impression cylinder and adjacent portions of the trip mechanism.

The invention is illustrated as applied to 50 a rotary lithographic press provided with a transfer cylinder 1 and an impression cylinder 2, these cylinders constituting the printing couple of the press. The cylinders rotate on shafts 3 and 4, which are journaled 55 in the usual manner in the frame of the

press. During the normal operation of the press the cylinders rotate in engagement with each other so that impressions are formed by the transfer cylinder upon the sheets fed between the cylinders. As is customary in presses of this kind, however, means are provided for throwing the cylinders out of operative engagement with each other to prevent offsetting upon the impression cylinder when the press rotates without any sheet between the cylinders.

The cylinders are thrown out of engagement by moving the axis of the transfer cylinder away from the axis of the impression cylinder, and for this purpose the shaft 3 70 has bearings in eccentrics 5 which may be rotated in the frame of the press. The eccentrics are controlled primarily by hand levers 6, which are fixed to the ends of a rock shaft 7. The levers 6 are connected at their 75 upper ends by links 8 with upwardly-extending arms 9 on the eccentrics 5, so that the eccentrics may be partially rotated by means of either hand lever. In Fig. 1 the throw-out mechanism is illustrated in such 80 position that the transfer cylinder has been moved out of engagement with the impression cylinder. To throw it into engagement again the hand lever 6 is swung to the right. This causes the eccentrics to rotate to the 85 left and the axis 3 is moved slightly in a nearly horizontal direction from left to right, and the cylinders are engaged.

The movements of the hand levers are limited by two stop-screws 63 and 64 on the 90 frame of the press, and the stop-screw 63 is adjusted to permit the hand levers to be moved to a position in which the levers 6 and the links 8 are nearly in a straight line but slightly beyond dead-center position, so 95 that the thrust of the links 8 tends to maintain the parts in position with the cylinders in engagement.

The throw-out mechanism, apart from certain automatic features peculiar to the 100 present invention, is constructed in accordance with my invention disclosed in Letters Patent of the United States Number 913,119, issued February 23, 1909. This mechanism is arranged to throw out the printing couple 105 by power derived from the mechanism of the press in timed relation with the operations of the printing couple, so as to act after the completion of one impression and before the commencement of another.

The throw-out mechanism acts through the mechanism above described for moving the eccentrics 5, and for this purpose one of the hand levers 6 is provided with an arm 10 connected with the upper end of a link 11. The lower end of the link is pivoted to an arm 12 fixed to a rock-shaft 13.

The power for throwing out the transfer cylinder is derived from the impression cylinder by a segment 14, which is fixed to the rock-shaft 13. This segment has a curved friction surface adapted to engage the periphery of the cylinder near one end thereof, and when this engagement occurs the cylinder, by its rotation in the direction of the arrow in Fig. 1, swings the segment to the right, as in the drawing, thereby rotating the rock-shaft 13 and depressing the arm 12. This causes the link 11 to pull the hand lever 6 into its left-hand position so as to throw out the transfer cylinder.

In the normal operation of the press, the segment 14 is out of engagement with the cylinder and is in its left-hand position. Its operation is controlled by raising it into engagement with the cylinder at the proper moment, and for this purpose the rock-shaft 13 upon which it is mounted is journaled in a movable support. This support has the form of a bell-crank lever 15, which is pivoted on a stud 16 on the frame of the press. A spring 17 attached to the lever 15 acts normally to swing it to the right, so as to lower the shaft 13 sufficiently to disengage the segment from the cylinder.

The mechanism for moving the segment into operative position comprises an arm 18 on the bell-crank lever 15. This arm carries a pivoted guide 19, through which a rod 20 passes loosely. This rod is connected with a treadle lever 21, which is pivoted at 22 to the frame of the press. A compression spring 23 connects the guide 19 with nuts 24 on the upper end of the rod 20.

When the treadle lever 21 is depressed, the spring 23 is compressed and it tends to depress the arm 18 and throw the segment 14 into operation. In order that this operation may occur at the proper time, however, the movement of the bell-crank lever 15 is controlled by a cam mechanism. The lever 15 has an arm 25 carrying a cam roll 26; which is adapted to engage a cam 27 mounted on a shaft 28. The shaft 28 and the cam are rotated constantly by suitable gearing connected with the mechanism of the press in timed relation with the operations of the printing couple. By means of a suitable depression in the cam, the cam roll is permitted to drop at the proper moment, so as to release the bell-crank lever 15 and permit it to be moved under the influence of the spring 23 to throw the segment 14 into engagement with the impression cylinder.

In the construction disclosed in the appli-

cation above referred to the treadle lever is depressed by the operator of the press to secure the results above described, but in the present invention I provide a trip mechanism which performs this operation automatically whenever there is failure on the part of the operator or of the feeding devices to supply a sheet at the proper time to receive the impression.

The impression cylinder 2 is provided with grippers 38 of ordinary construction, and these grippers seize the forward edge of the sheet 39, which is fed from a feed table 41 in any ordinary or suitable manner. The operation of the trip mechanism is controlled by one or more feelers which engage the sheet near its forward edge. As shown in the drawings, a feeler 42 is mounted on a rock-shaft 44 which is journaled longitudinally within the impression cylinder. This feeler has an angular extremity which occupies a recess 43 in the cylinder at one side of one of the grippers 38, so that when a sheet is held by the grippers the feeler may engage the forward margin of the sheet.

The feeler is actuated by an arm 45, which is fixed to the rock shaft at the end of the impression cylinder. This arm carries a cam roll 47 engaging a cam 48, which is fixed to the frame of the machine and surrounds the shaft 4. A tension spring 46 is fixed at one end to the arm 45 and at the other end to a fixed pin 65, and this spring tends constantly to move the arm 45 to the left (in Fig. 3) so as to maintain the cam roll in engagement with the cam. As the impression cylinder rotates, carrying the rock-shaft and the arm 45 with it, the cam roll traverses the cam. The greater part of the cam is circular, and while the roll traverses this circular part, the mechanism occupies the position of Fig. 3, in which the feeler 42 is lowered below the position occupied by the sheet 39. At one point, however, the cam has a short depression 49, and when the cam roll reaches this point the spring 46 tends to pull the arm 45 to the left and thereby to turn the rock-shaft 44 and to elevate the feeler to the position shown in dotted lines in Fig. 3. In the presence of a sheet, however, the feeler is arrested by its engagement with the sheet, so that the arm 45 cannot be moved to the left.

In order that the trip mechanism may actuate the throw-out mechanism, the arm 45 is provided with a trip 51 adapted to engage a lug 52 on the inner side of a slide 53. The slide is mounted to slide longitudinally in guides 54 in a frame-member 55 which is secured to the ordinary frame of the press. The slide 53 is pivoted to one arm 56 of a bell-crank lever which is pivoted on the frame member 55. The other arm 57 of the lever is connected by a link 58 with a depending arm 59, which is fixed to a rock-

shaft 61. The rock-shaft is journaled on the frame of the press and it carries a detent 36 on its outer end. This detent acts normally to hold the throw-out mechanism out of operation. A spring 62 connected with the lever arm 57 tends normally to hold the parts in the position of the drawings, with the slide 53 depressed and the detent in operative position.

10 The means for depressing the treadle lever to operate the throw-out mechanism comprise a rod 31, which is pivoted at its lower end to the treadle lever and at its upper end to a block 32 fixed to a slide rod

15 33. The slide rod moves vertically in lugs 34 on the frame of the press, and a powerful tension spring 37, which is attached to the lower end of the slide rod, tends to depress the slide, the rod 31 and the treadle lever.

20 This downward movement is normally prevented, however, by the detent 36 above described, which engages a lug 35 on the slide rod when the latter is in its normal raised position.

25 The operation of the apparatus as a whole occurs as follows: With the parts in normal position, suppose the operator fails to supply a sheet to the printing couple at the moment when the grippers are in position

30 to receive it. Immediately after the closing of the grippers the cam roll 47 of the trip mechanism enters the depression on the cam 48, and as the feelers are not arranged by a sheet, the arm 45 swings momentarily to the

35 left at the time when the trip 51 and the lug 52 are in position to engage each other. The trip 51, therefore, engages the lug momentarily and, owing to its rotation with the impression cylinder, it raises the lug and the

40 slide 53. Through the connections above described the detent 36 is thus moved momentarily to the left, so as to release the slide rod 33, and the spring 37 and rod 31 act to depress the treadle lever and throw the

45 throw-out mechanism into operation. These operations all occur nearly simultaneously, so that the transfer cylinder 1 is thrown out before the impression surface of the impression cylinder reaches the transfer cylinder,

50 and thus the offsetting of an impression on the bare impression cylinder is prevented. After an operation of the trip mechanism the treadle lever and the slide rod 33 are raised to normal position by means of a handle 66 fixed to the block 32 on the slide rod and the impression cylinder is restored to printing position by the handle 15', as above described.

Various modifications may be made in the 60 embodiments of my invention hereinbefore described and illustrated in the drawings, within the nature of the invention and the scope of the following claims.

I claim:

65 1. An automatic trip mechanism for print-

ing presses comprising, in combination with the rotary impression cylinder of a press, stationary throw-out mechanism for throwing out the printing couple of the press, said mechanism including a movable member by which it is thrown into operation, a feeler located within the impression cylinder and constructed and arranged to engage the margin of a sheet carried by the cylinder, and a tripping device connected with the feeler carried by the cylinder and extending outwardly at the end of the cylinder in position to engage and move said movable member of the throw-out mechanism.

2. An automatic trip mechanism for printing presses comprising, in combination with the rotary impression cylinder of a press, throw-out mechanism for throwing out the printing couple of the press, said mechanism being constructed and arranged to be actuated by the power of the press and in timed relation to the operation of the press, a feeler carried by the impression cylinder and constructed and arranged to engage a sheet carried by the impression cylinder, and tripping means controlled by the feeler and actuated by the impression cylinder in its rotation, said means acting to render the throw-out mechanism operative when there is no sheet upon the impression cylinder.

3. An automatic trip mechanism for printing presses comprising, in combination with a moving member of the printing couple of a printing press, stationary throw-out mechanism for throwing the press out of operation including a movable member controlling the throw-out mechanism, a feeler carried by the moving member of the printing couple and constructed and arranged to engage the inner surface of a sheet carried by said member, a tripping device connected with the feeler and adapted to engage and actuate the movable member to render the throw-out mechanism operative when there is no sheet on the moving member of the printing couple, and means tending to actuate the tripping device.

4. An automatic trip mechanism for printing presses comprising, in combination with the rotary impression cylinder of a press, stationary throw-out mechanism for throwing out the printing couple of the press, said mechanism including a movable member by which it is thrown into operation, a feeler located within the impression cylinder and constructed and arranged to engage the margin of a sheet carried by the cylinder; and a tripping device comprising a slidale member connected with the movable member, a trip connected with the feeler and adapted to engage and actuate the slidale member when the feeler moves outwardly in the absence of a sheet, and means tending to cause the trip to actuate the movable member.

- 4
5. An automatic trip mechanism for printing presses comprising, in combination with the rotary impression cylinder of a press, stationary throw-out mechanism for throwing out the printing couple of the press, said mechanism being constructed and arranged to be actuated by the power of the press, a feeler carried by the impression cylinder and constructed and arranged to engage the inner surface of a sheet carried by the impression cylinder, tripping means carried by the feeler and adapted to actuate the throw-out mechanism when the feeler moves outwardly in the absence of a sheet from the impression cylinder, means tending to move the feeler outwardly and means arranged to permit the feeler to move outwardly in timed relation to the operation of the press.
6. An automatic trip mechanism for printing presses comprising in combination with the rotary impression cylinder of a press, stationary throw-out mechanism for throwing out the printing couple of the press, said mechanism being constructed and arranged to be actuated by the power of the press, a feeler carried by the impression cylinder and constructed and arranged to engage the inner surface of a sheet carried by the impression cylinder, an actuating arm of the feeler, a trip connected therewith adapted to engage and actuate the throw-out mechanism as the feeler is moved outwardly in the absence of a sheet from the impression cylinder, means tending to move the feeler outwardly, and a cam coöperative with the actuating arm to permit the feeler to move outwardly only when the trip is in position to engage and actuate the throw-out mechanism.
7. An automatic trip mechanism for printing presses comprising, in combination with the printing couple of a press including a movable impression member, stationary throw-out mechanism constructed and arranged to move one member of the couple away from the complementary member, said throw-out mechanism including a movable member by which it is thrown into operation, a feeler carried by the impression member and constructed and arranged to engage the inner surface of a sheet carried by the impression member, an actuating arm connected to the feeler, means coöperating with the actuating arm tending to move the feeler outwardly, a trip actuated by the actuating arm and adapted to engage and actuate the movable member of the throw-out mechanism as the feeler is moved outwardly, and a cam coöperative with the actuating arm and arranged to permit the trip to actuate the movable member of the throw-out mechanism in timed relation to the operation of the press.

In testimony whereof, I have affixed my signature in presence of two witnesses.

ALBERT J. FORD.
